JAMES H. TODD, OF BROOKLYN, NEW YORK, AND GEORGE F. WHEELER, OF RIVERSIDE, CONNECTICUT

FLOATING AIRPORT

Application filed August 1, 1929. Serial No. 382,697.

This invention relates to floating airports and our improvements are directed to floats having a fixed ramp that is partly submerged and adapted to facilitate the operation of hauling a seaplane or the like upon the deck 5 of the float and its return to the water.

Further our improvements are directed to means functioning under the influence of air pressure to maintain a moored float in position with its ramp lying in the direction of the wind, so that a seaplane or the like alighting on the water surface against the wind can be pointed toward the ramp.

Further our improvements include power 15 means upon the float so that when moored in tidal waters or where currents exist it can be swung to present its ramp toward an approaching seaplane or the like.

Further our improvements comprise means 20 in connection with the mooring means to facilitate the directional control of the float.

Other features and advantages of our invention will hereinafter appear.

In the drawings:

25 Figure 1 is a side elevation of a float equipped with our improvements, and

Figure 2 is a plan view thereof.

In said figures let 1 indicate the hull of a float intended for use as an airport, the 30 main deck 2 of said float having at one end, which may be the stern, a ramp 3 whose outboard end extends below the surface of the water to permit seaplanes and the like to be hauled up the ramp and on to the deck.

35 It is desirable that the float, when moored at its end opposite the ramp end shall be provided with means for holding said ramp end pointed in the direction of the wind, and therefore, for use in non-tidal waters and

40 where there are no currents, we employ a vertical vane or wind board, indicated at 4, that is positioned along the longitudinal centre of the float, and is elevated sufficiently above the deck to permit a seaplane or 45 the like to pass thereunder. Outrigged stanchions 5 are indicated as means for supporting vane 4. When the float is moored in tidal waters or where currents exist we provide power means carried by the float for 50 swinging said float about its end mooring to

point the ramp end in the wind direction.

For this purpose we have shown a motor 6, preferably located below the main deck, toward the ramp end of the float, and a propeller operable thereby, said screw being 55 carried by a shaft that extends through the side of the hull. When the float has been swung into the wind by means of the propeller 7 it can be held in that position by an anchor 8 that is then lowered from the opposite side of the float. A windlass, having suitable operating means, is indicated at 9 for lowering and raising anchor 8. The mooring means herein illustrated as applied to the float end opposite the ramp comprise 60 an anchoring spud 10, and four mooring standards 11 disposed concentrically thereabout.

A ball bearing ring 12 is freely revoluble 70 on the spud 10, being supported thereon by a fixed annular bearer 13. Said ring 12 has hinged connection, indicated at 14, with a rigid V bridle 15 that is hinged at separated points 16 to the hull end at about the deck level, thereby allowing the float to ride freely 75 at varying tide levels.

At each of four points on the radius of the swing of the float's anchored end there is located a mooring standard 11, said standards being so positioned that they are clear of 80 the hull at all times.

To the head of each of the four mooring standards 11 there is fitted suitable means of securing the ends of an operating cable 17. Said cable 17 passes over sheaves 18 that 85 are installed on the outboard ends of rigid steel outriggers 19, thence passing over roller sheaves 20 to a motor operated winch 21 that is located within the hull.

By slackening off the swinging or operating 90 cable on one side and hauling by means of the winch on the cable at the opposite side the float can be brought into the direction of the wind and held there by keeping the strain on the hauling side against tide or 95 current. The mooring ends of the operating cable can be in the form of a bridle 22, so that connection can be made to two mooring standards 11 at one time, whereby before one mooring is cast off the mooring desired 100

can be made when preparing to swing the float.

At 23 we have indicated a hangar, and at 24 a machine shop. Other facilities appreciably can be provided on the float. Variations within the spirit and scope of our invention are equally comprehended by the foregoing disclosure.

We claim:

1. The combination with a float having a ramp at one end thereof and mooring means at its other end, of mooring standards positioned concentrically about said mooring means, and means carried by said float to co-act with said mooring standards for swinging said float into an adjusted position.

2. The combination with a float having a ramp at one end thereof and anchoring means at its other end, of mooring standards positioned concentrically about said anchoring means, means carried by said float to co-act with said mooring standards for swinging said float into an adjusted position and means for holding said float with its ramp pointed in the direction of the wind.

3. The combination with a float having a ramp at one end thereof and anchoring means at its other end, a plurality of mooring standards positioned concentrically about said anchoring means, a bridle having one end connected to said float and having its other end rotatably borne by said anchoring means, whereby the front of said float is clear of the standards at all times and means carried by said float to co-act with said standards for swinging said float into an adjusted position.

New York, July 31, 1929.

JAMES H. TODD.
